PICK COUNTER

Harvey L. Spaunburg, West Hartford, Conn., assignor to Veeder-Root Incorporated, a corporation of Connecticut

Original application January 28, 1938, Serial No. 187,355. Divided and this application September 12, 1940, Serial No. 356,431

1 Claim. (Cl. 235—144)

My invention relates to resettable pick counters and is a division of my copending application Serial No. 187,355, filed January 28, 1938, and now abandoned.

It has heretofore been proposed to prevent advancement of the count of a pick counter by a sharp blow on the resetting member through providing a clutch between the resetting member and the resetting shaft. However, in this construction, the mechanism has been such that while, as heretofore, preventing advancement of the counter wheels by a blow when the counter is locked, a new difficulty has been encountered; this structure making it possible for the counter wheels thus to be advanced by a blow when the counter is unlocked. This is due to the fact that the clutch has been under control of the key, and that the clutch mechanism has been such that the clutch elements, while entirely separated when the counter is locked, have been engageable to produce a positive driving connection when the key is operated to unlock the counter. As a result, while a dishonest operator without a key cannot advance this counter fraudulently by hammering the resetting member, another dishonest operator who obtains a key can so advance it by merely unlocking the counter, striking the resetting member a blow to advance the count while holding the shaft against advance, and then re-locking the counter so that no one knows what has happened.

My invention has among its objects to provide an improved pick counter of the blow-proof type which is blow-proof both when the counter is locked and unlocked and which is, accordingly, free from the above objections.

A further object of my invention is to provide such an improved counter including a clutch and wherein the clutch, as distinguished from being intermittently connected, is constantly connected, and yet wherein the elements of the clutch cannot be brought into positive engagement in such manner as to transmit the impact of a blow on the resetting member to the resetting shaft.

A still further object of my invention is to provide such improved operative connections between the reset operating member and the resetting shaft whereby, while obtaining these advantages, the construction is such as to be readily and inexpensively applied to standard counters without change in the mechanism within the counter casing or in any way requiring the use of special mechanism within said casing.

These and other objects and advantages of my

improved construction will, however, hereinafter more fully appear.

In the accompanying drawing I have shown for purposes of illustration one embodiment which my invention may assume in practice.

In the drawing:

Figure 1 is a plan view of a double locked pick counter having my improvements; part of the counter being broken away to facilitate illustration; 10 and certain parts being shown in section;

Fig. 2 is an enlarged sectional view on line 2—2 of Fig. 1;

Fig. 3 is a sectional view on line 3—3 of Fig. 2;

Fig. 4 is a sectional view on line 4—4 of Fig. 2;

15 Fig. 5 is a perspective view showing the parts of the clutch separated, but in their correct relation;

Fig. 6 is a sectional view on line 6—6 of Fig. 1;

Fig. 7 is a greatly enlarged sectional detail 20 showing one of the recesses in the friction disc and a cooperating projection or detent on the friction plate, and

Fig. 8 is a sectional view on line 8—8 of Fig. 1 with parts broken away to illustrate details of 25 a counter wheel clutch and the resetting elements associated therewith; the wheel being shown in zero position.

In this illustrative construction, I have shown 30 a pick counter including a rectangular casing 1, open at the top, having a cover 2 forming a closure for the open top, and including two counter mechanisms located in side by side relation therein, generally indicated at A and B, each having a resetting shaft 3 on which a plurality of operatively connected counting units 4 are rotatably mounted.

Locking mechanism is provided in the casing, 35 including a key operated lock 5 controlling a locking bar 6 disposed transversely to and controlling the operation of the resetting shafts 3, and improved clutch means, generally indicated at C, is also provided between the resetting shafts 3 and the usual manually rotatable wing nuts 7 external of the casing.

40 The counters A and B are identical, and, accordingly, a description of the counter A will suffice. The resetting shaft 3 of the counter is journaled in bosses 8 in the end walls of the casing, one of which is shown in Fig. 2, and is provided with the usual longitudinal resetting groove 9 which cooperates with resetting pawls 10 (Fig. 8) in the counting units 4, in a usual manner. The counting units 4 are of a usual construction including a number wheel 11 carrying a two-tooth gear 12 and having a twenty-tooth gear 13 rotat-

ably mounted on a hub thereof and connected thereto through a clutch connection including a cup-shaped ratchet 14 and spring urged pawls 15; the usual transfer pinion 16 being provided to connect the proximate twenty-tooth and two-tooth gears of adjacent counting units.

A rotatable locking member 17 is carried on the resetting shaft 3 having a key which enters the groove 9 so that the locking member rotates with the shaft. A sleeve 18 of the locking member abuts a flat key 19 adjacent the left-hand boss 8 having a bifurcated lower end 20 disposed in an annular groove 21 in the shaft 3 for positioning the shaft against axial movement in the casing. The locking member 17 also has an annular flange 22 provided with teeth 23 which cooperate with a pawl 23a carried by the transfer pinion shaft 16a for preventing reverse rotation of the resetting shaft in certain positions of the latter. This flange also serves to position the locking bar 6 (Fig. 6), which overlies the locking portion 24 of the member and is positioned between the flange 22 and washers 25 abutting the shoulder formed by the locking portions; a spacing sleeve 26 being provided between these washers and the highest order counting unit. The locking portion 24, which is generally annular, is provided with right angularly related flat surfaces 27 on its circumference which are engaged by corresponding angularly related flat surfaces 28 on the locking bar 6 when the latter is moved into locking position.

A key operated lock is provided between the counters A and B having a rotatable barrel 30 journaled in a boss 31 on the casing end wall and carrying a washer-shaped cam 32 having a key 33 projecting into the key slot 34 in the barrel. The cam 32 has a nose 35 which acts on the bar 6 to slide the latter in opposite directions upon rotation of the lock barrel between locked and unlocked positions; the locked and unlocked positions of the bar being shown in full and dotted lines respectively in Fig. 6. This locking structure per se forms no part of this invention; being described and claimed in my Patent No. 2,193,159 of March 12, 1940.

Improved means are provided between the wing nut 7 and the resetting shaft 3 for transmitting a manually applied resetting rotation of the wing nut to the shaft while preventing the transmission of force thereto due to a blow on the wing nut. The clutch C and the wing nut 7 are carried on the resetting shaft 3 externally of the casing 1. Referring to Fig. 2, it will be noted that the casing 1 is provided with an annular external finished surface 44 forming a slight recess concentric with the resetting shaft 3 which provides a bearing for a hub 45 secured by a pin 46 to the shaft; the ends of the pin 46 (Fig. 3) being ground off flush with the circumference of the hub. The hub 45 has a closed end, spaced from the end of shaft 3, having an axial passage therethrough smaller than shaft 3 to receive a stud 48. The stud 48 has an enlarged head 49 of the same diameter as shaft 3, which completely fills the space between the end wall of the hub and the shaft and projects through the aperture 47 a substantial distance. The hub 45 also has integral therewith a friction disc 53 which lies close to the end wall of the casing 1, and, as shown most clearly in Fig. 4, is provided with spaced recesses 51 arranged radially on the outer face thereof and having beveled side walls 52; the shape of these beveled walls being clearly shown in Fig. 7.

A friction plate 53 is journaled on the hub 45 adjacent the friction disc 50 and is provided with cooperating pressed-out projections 54, one of which is provided for each of the recesses 51 in the friction disc. It will be noted from Fig. 7 that these projections, which are receivable in the recesses 51, are generally arcuate in configuration and are provided with cut away flat faces 55 in the plane of the friction disc which are hence parallel with the bottom of the recesses 51, but are slightly spaced therefrom. The friction plate 53 is constantly pressed into engagement with the friction disc 50 by means of a coiled spring 56 which bears against the outer face of the plate on one end and against an inside face of a housing 57 at its other end. The housing has an annular external cover portion 58 which encloses the spring, friction plate, and friction disc and terminates at its edge closely adjacent the end wall of the counter casing 1, and an internal sleeve 59 which is journaled on the hub 45. The housing member 57 also has an oppositely extended sleeve 60 of reduced diameter in which the stud 58 is closely received; a shoulder 61 being provided between the different diameter sleeves 59 and 60.

The wing nut 7 is provided with an externally tapered hub 62 having an axial bore 63 which receives closely the sleeve 60 of the housing member; a pin 64 being extended through the hub 62, sleeve 60, and stud 48 so that the wing nut, stud, and housing rotate as a unit. It will be noted, however, that by reason of the head 49 within the closed end of hub 45, the unit is held against displacement from this hub on which it is journaled. As shown most clearly in Figs. 3 and 5, the friction plate 53 is provided with three angularly related ears 65 which engage flat built-up portions 66 on the inside of the portion 58 so that the friction plate 53 rotates with the housing 57.

In the operation of my improved pick counter resetting mechanism, it will be noted that when the counter is unlocked and the locking bar 6 is in the dotted line position shown in Fig. 6, the rotation of the wing nut 7 causes the housing 57 to rotate and rotate with it, as a unit, the friction plate 53, friction disc 50, and shaft 3 to cause the slot 9 in shaft 3 to pick up the resetting pawls 10 of the several counting units and return them to zero. When, however, the bar is moved to the position shown in full lines in Fig. 6, in which the flat faces 28 are in engagement with the flat faces 27 of the rotatable locking members, the shafts 3 are held by these locking members against rotation, and rotation of the wing nuts 7 will cause the projections 54 on the friction plate 53 to be cammed out of the recesses 51; the spring 56 yielding to permit rotation of the friction plate relative to the friction disc 50. It will be noted that the wing nut 7 can be rotated in either direction when the counter is locked and that a blow struck on wing nut 7 in either direction of rotation will not transmit sufficient torque to the shaft 3 to jump ahead any counting wheel even if the pawl 16 of that wheel should happen to be in the groove 9.

As a result of my improved construction, both when the counter is locked and when it is unlocked, the counting wheels cannot be advanced by a blow struck on the wing nut 7. Assuming the counting wheels to be in their zero position just following resetting, it will be evident that if a blow is struck on the wing nut in an attempt to advance a counting wheel without advancing the

resetting shaft, any blow which is sufficient to overcome the inertia of the clutches of the counting wheels will first result in slipping the friction plate 53 over the friction disc 50; the construction of the projections 54 being such that a normal turning torque on the wing nut 7 will be transmitted to the reset shaft 3 by means of the cooperating friction plate and friction disc, while any suddenly applied force, as a blow, will result in camming the projections 54 out of the recesses 51. Thus, with the inertia of the clutch C less than the inertia of the clutches in the counting units, it is impossible under any circumstances to advance the counting wheels by a blow on the wing nut 7. This is partly due to the arcuate configuration of the projections 54 and the bevel of the walls 52 of the cooperating recess 51, and partly due to the removal of the tops of these projections to form the flat portions 55. As a result of the latter, the cooperating plate and disc will transmit manual rotation of the wing nut 7, but the friction plate will slip relative to the friction disc 50 before the tension of spring 56 has greatly increased due to its compression. This results in making the clutch C very sensitive to forces applied by a blow.

While I have in this application specifically described one embodiment which my invention may assume in practice, it will be understood that the same is shown for purposes of illustration and that my invention may be modified and embodied in various other forms without departing from its spirit or the scope of the appended claim.

I claim as my invention:

In a pick counter, a resetting shaft; a plurality of counter units of successive order rotatably mounted on said shaft and each having a numeral wheel, a driven gear, and a ratchet clutch between the wheel and the driven gear; reset pawls carried by said wheels and adapted to cooperate with said shaft when the latter is turned in a resetting direction, a transfer pinion between adjacent units, an operating member rotatably mounted on one end of said shaft for turning the latter in a resetting direction to effect a resetting operation of said wheels, and a resetting clutch between said operating member and shaft and including two clutch members respectively connected to the operating member and shaft for rotation therewith, one of said clutch members having recesses and the other of said members having arcuate projections normally engaging in said recesses, and a spring for resiliently urging said clutch members into engagement with one another with such pressure that when the operating member is rotated manually during a resetting operation the clutch will remain in normal engaged position to transmit a resetting torque to the shaft and when a sudden sharp blow is imparted to the operating member the projections will ride out of said recess without exerting a sufficiently sustained transmission torque to overcome the friction of the ratchet clutches and the tendency of the wheels to remain at rest.

HARVEY L. SPAUNBURG.
